GAME TABLE

Gene S. Tepper, San Francisco, Calif., assignor to Michael Saphier Associates Inc., New York, N.Y., a corporation of New York

Filed Sept. 12, 1960, Ser. No. 62,106

Term of patent 3½ years

(Cl. D33—14)

I claim:

The ornamental design for a game table, as shown.
